Application September 11, 1946, Serial No. 696,090

10 Claims. (Cl. 153—6)

1

This invention relates to apparatus for shaping electrical coils and, as one of its objects, aims to provide an improved apparatus of this kind which is relatively simple in its construction and operation but which will accomplish the coil shaping operation rapidly and with a desired uniformity for the shaped coils.

Another object of the present invention is to provide improved apparatus for rapidly and economically bending or shaping electrical coils, and particularly coils of the inductor bar type intended for use in the armature members of generators or other electrical machines.

A further object of this invention is to provide improved apparatus of this kind, in which a number of such coils can be subjected to the desired shaping operation simultaneously and during which the coils preferably are disposed in a group or arrangement corresponding generally with their arrangement in the electrical machine in which they are ultimately assembled.

Still another object is to provide a coil shaping apparatus of this character, in which relatively movable die members are employed and have cooperating rows of slots in which corresponding portions of the coils of a group or series engage so that the relative movement of the die members will cause bending of such corresponding portions of all of the coils simultaneously and to substantially the same extent.

The invention can be further briefly summarized as consisting in certain novel combinations and arrangements of parts hereinafter described and particularly set out in the claims hereof.

In the accompanying sheets of drawings,

Fig. 1 is a plan view showing coil shaping apparatus embodying the present invention;

Fig. 2 is a vertical section taken through the apparatus substantially on the line 2—2 of Fig. 1;

Fig. 3 is a horizontal section taken on line 3—3 of Fig. 2 and showing the pair of relatively rotatable die members with the coils engaging in the slots thereof;

Fig. 4 is a sectional view looking toward the slotted portion of the third die member as indicated by line 4—4 of Fig. 2;

Fig. 5 is another horizontal section taken on line 5—5 of Fig. 2 and showing the relation of the ejector means to the sleeves which carry the die rings;

Fig. 6 is a fragmentary sectional view of the three cooperating die members showing the same on a larger scale, the view being taken substantially as indicated by line 6—6 of Fig. 3;

Fig. 7 is a plan view of one of the work coils

before being subjected to the shaping operation;

Fig. 8 is an end view of the coil looking toward the open end thereof;

Fig. 9 is a plan view of the same coil after having been subjected to the shaping operation; and

Fig. 10 is an end view of the shaped coil looking toward the closed end thereof.

The improved apparatus 20, as described in greater detail hereinafter, can be used to perform a shaping operation on various kinds of electrical coils and is especially suitable for performing operations of this character on coils which are used in the armature members of generators or other electrical machines. The expression "armature member" as employed herein is used in a broad sense in which it is intended to include any rotor, stator, armature or electrical machine part containing shaped coils. The coils employed in such an armature member may consist of only a single turn of copper wire of relatively heavy cross section and in which certain portions of the coil form inductor bars. Coils fabricated for this use are required to be shaped or bent so that the ends or connecting portions thereof will be offset with respect to the inductor bar portions, as is well understood by those skilled in the electrical art.

By way of example, Figs. 7 and 8 of the drawings show one form of electrical coil 10 with which the present apparatus 20 can be used to advantage for the desired shaping operation. Figs. 7 and 8 show the coil 10 in its initial form, and Figs. 9 and 10 show the same coil after it has been subjected to a shaping or forming operation by the improved apparatus. As shown in Figs. 7 and 8 the coil 10 is made of wire of a substantially rectangular cross section, and in its initial form the coil is of the so-called "hairpin" shape having a pair of spaced substantially parallel legs 10a and 10b. At the closed end of the coil, these legs are connected by a 180° bend 11 of relatively small radius so that the intervening space 12 between the adjacent legs is relatively narrow. The legs 10a and 10b can be of substantially the same length or, as here shown, the leg 10a is slightly longer than the leg 10b. In the initial form of the coil as shown in Figs. 7 and 8, the legs 10a and 10b, as well as the connecting bend 11, all lie in substantially the same plane.

As mentioned above, Figs. 9 and 10 show the coil 10 after the shaping operation has been performed thereon by the improved apparatus. Dur-

ing the shaping operation, the coil 10 is rotated

ing the shaping operation, as will be explained in greater detail hereinafter, the legs 10a and 10b are spread apart in a direction substantially normal to their common plane by the forming of two bends 13 and 14 in each of these legs. The bend 14 is formed in the legs at a point relatively close to the connecting bend 11 while the bend 13 is spaced somewhat further from the bend 11. Each of the bends 13 and 14 is somewhat greater than a right angle and when they have been formed in the legs the coil 10 has what can be conveniently termed a "wish-bone" shape in which leg portions of substantial length constitute substantially parallel inductor bar portions 15. The particular coil 10 shown in this instance is intended for use in the slots of a stator (not shown) for an alternating current generator in which a field rotating in the stator induces electrical currents in the inductor bar portions 15. When the coils are assembled in the stator the inductor bar portions 15 extend through annularly spaced axial slots in the wall of the stator and their projecting straight ends are subjected to a further bending operation, by apparatus other than that disclosed herein, before the electrical connections are made thereto.

The improved coil shaping apparatus 20 includes a die mechanism 21 which is mounted on a suitable frame or base plate 22. The apparatus also includes actuating and ejector cylinders 23 and 24 which are also connected with the base plate 22 and are controlled by valves 25 and 26 respectively. The base plate 22 can be a slab or plate of any appropriate size or shape and can be supported by any suitable means such as the top 27 of a work bench or conveyor table.

The die mechanism 21 comprises a pair of inner and outer die rings 28 and 29 relatively rotatable about a common axis 59 and a third die ring 30. The die rings 28 and 29 are disposed in opposed or coextensive coaxial relation to each other and are carried and actuated by coaxial stationary and rotatable sleeves 31 and 32 respectively. The sleeve 31 is connected with the base plate 22 in fixed relation thereto by being mounted on a hollow block or bushing 33 which extends through an opening 33a of the base plate and is anchored therein as by means of a retaining screw 34 which is threaded into the base plate and has a locking projection 35 extending into a radial opening of the bushing. The lower end of the stationary inner sleeve 31 surrounds the upper end of the bushing 33 in relatively close fitting relation thereto and is connected with the bushing by means of the dowel pins 40.

The rotatable sleeve 32 is carried by an actuating gear or gear sector 37 having a central opening 37a by which it is rotatably mounted on the bushing 33. The gear 37 is located above the base plate 22 and is slidably supported by the upper face 22a thereof. The sleeve 32 can be connected with the gear 37 by having its lower end welded thereto as indicated at 39. The lower end of the sleeve 31 forms an external annular shoulder 41 on the bushing 33 which is spaced above the surface 22a of the base plate 22 to form the guideway in which the gear 37 operates.

In the construction above described, the sleeves 31 and 32 extend above the base plate 22 in upright coaxial relation with an annular space 43 therebetween. The die rings 28 and 29 are mounted on the upper ends of the sleeves 31 and 32, as by means of the screws 44 and 45, with the outer periphery 28a of the die ring 28 in op-

5 posed or coextensive relation to the inner periphery 29a of the die ring 29. These opposed peripheral portions of the die rings overhang the annular recess 43 and extend substantially into meeting relation with each other.

As shown in Fig. 3 the periphery 28a of the inner die ring 28 is provided with a series of annularly spaced radial slots 46, and similarly the inner periphery 29a of the outer die ring 29 is provided with a series of annularly spaced radial slots 47. The slots 46 and 47 are of a size and shape such that when the slots of one series are in opposed or complementary relation to the slots of the other series, the legs 10a and 10b of the coil 10 can be readily inserted thereinto.

The die rings 28 and 29 can be of any appropriate depth or thickness so as to provide the necessary bearing engagement with the legs of the coils 10 to accomplish the desired bending operation thereon. In this instance these die rings engage the legs 10a and 10b of the coils for a portion only of their length while the remaining portions of the legs extend downwardly into the annular space 43. This annular space also accommodates an annular ejector member 49 which, in its retracted position shown in Fig. 2, forms a support for the lower or open ends of the coils 10. When the legs of the coils are of different lengths as shown in Fig. 7, the 20 ejector member 49 is constructed with an annular recess 49a thereon into which the longer legs 25 of the coil extend.

When the adjacent peripheries 28a and 29a of the die rings 28 and 29 are constructed with the 30 slots 46 and 47 therein as described above, the intervening portions of these peripheries form annular rows of teeth 50 and 51. To prevent portions of any of the coils from being accidentally subjected to shearing, or from causing jamming, 35 between the teeth 50 and 51 of the two die rings during relative rotation thereof, one of the die members, preferably the inner die member 28, is provided with a retaining band or rim 52. This 40 rim can be mounted on the periphery of the die ring 28 by suitable connecting means or can be shrunk thereon. The rim 52 extends in continuous relation around the die ring 28 and across the slots 46 thereof. The inner periphery of the 45 outer die ring 29 lies in relatively close relation to the rim 52 so that this rim also extends across the slots 47 and may be slidably engaged by the 50 tops of the teeth 51.

The third die ring 30 is carried by a block or 55 weighted body 54 which is liftable relative to and detachable from the die rings 28 and 29. The body 54 has a head portion 54a to which the die ring 30 is attached by means of screws 55 and stem portion 56 which is rotatable and axially slid able in the stationary inner sleeve 31. The body 54 60 is provided at its upper end with a suitable lifting means or handle such as a screw-eye 57 having a stem 57a threaded thereinto. The third die ring 30 is provided on its lower face with a series of annularly spaced radial slots 58 which are spaced 65 from the common axis 59 such that this row of slots overlies the rows of slots 46 and 47 of the die rings 28 and 29 as shown in Fig. 2.

In the operation of the apparatus as thus far 70 described, the body 54 carrying the third die ring 30 is removed from the die rings 28 and 29 by being vertically lifted either manually or by suitable lifting apparatus. During this removing operation the lifting force is applied to the eye-boit or handle mentioned above. When the third 75 die ring 30 has been thus removed, the coils 10

having the initial shape shown in Figs. 7 and 8 are inserted into the slots of the die rings in the relation shown in Figs. 2 and 3, and when all of the slots have been filled, the coils will constitute a full annular series about the common axis 59. The body 54 is then replaced on the die rings 28 and 29 with the third die ring 30 engaging the tops of the coils 10 so that the bends 11 thereof extend into the slots 58. The weight of the body 54 holds this member in place relative to the die rings 28 and 29 and retains the bends 11 of the coils in the slots 58.

The outer sleeve 32 and the die ring 29 carried thereby are then rotated relative to the inner sleeve 31 and die ring 28 for a desired angular distance to subject the coils 10 to the bending operation. During this relative rotation, the legs of each coil are spread or stretched apart arcuately about the common axis 59 so that the bends 13 will be formed in the legs immediately adjacent the tops of the die rings 28 and 29 and the bends 14 will be formed in the legs immediately adjacent the third die ring 30. In the bending operation just described the third die ring 30 also serves as a holding means for the coils which maintains the tops thereof at the correct annular spacing so that the bends being made in the legs will all be of the same shape and extent.

During the bending operation above described, it will be understood that the third die ring 30 is rotatable relative to the stationary die ring 28 by reason of the fact that the stem 56 of the body 54 is capable of rotation in the stationary sleeve 31. No positive rotating movement is applied to the body 54 other than the force which is applied to the third die ring during the stretching or distortion produced in the coils 10. In other words, during the bending operation the third die ring 30 is rotated an angular distance approximately one-half of the angular rotation of the die ring 29 and this rotation of the third die ring is produced solely by the translatory movement of the tops of the coils which results from the pulling force which the movable die ring 29 applies to one set of legs of the coils while the other set is being held stationary by the stationary die ring 28.

The relative rotation between the sleeves 31 and 32 for actuating the die ring 28 is produced by an angular movement or oscillation of the gear 37. This gear can be driven by any suitable power means and in this instance is operably connected with a reciprocating rack 61 by means of an idler gear 62. The idler 62 is rotatably mounted on the base plate 22 by means of the pivot screw 63. The rack 61 is guided and held in meshing engagement with the idler 62 by a guide roller 64 which is rotatably mounted on the base plate by means of the pivot screw 65. The rack 61 is actuated by the above mentioned power cylinder 23. This is a double acting cylinder having a piston 67 operable therein and connected with the rack by means of the piston rod 68.

Suitable motive fluid under pressure, such as compressed air, is adapted to be supplied to or exhausted from the ends of the cylinder 23 through the connections 69 and 70 and the control valve 25. The valve 25 is of a conventional construction and controls the operation of the cylinder 23 such that movement of the handle 71 in one direction will cause rotation of the die ring 28 in one direction and movement of the handle in the opposite direction will cause rotation of the die ring in the other direction. The

cylinder 23 can be mounted on or connected with the base plate 22 by means of a suitable supporting rack or frame 72.

When the coils 10 have been subjected to the bending operation as described above, the body 54 carrying the third die ring 30 is removed from the shaped coils and the ejector member 49 is moved upwardly in the annular space 43 to lift or eject the coils with respect to the die rings 28 and 29. The ejector may be in the form of an inverted cup-shaped member whose rim or side wall forms the annular ejector member 49 and whose transverse bottom wall forms a connecting or mounting spider 74. The spider 74 has radial arms 75 which extend through axial slots 76 in the inner sleeve 31. The central portion of the spider 74 is connected to a sleeve or thrust member 76a by means of the screw 77 and this sleeve is, in turn, connected with the threaded outer end 78a of a piston rod 18 projecting from the ejector cylinder 24.

The ejector cylinder 24 is a double acting cylinder which extends in depending relation to the bushing 33 and may be mounted thereon by being provided with a threaded extension 79 which is screwed into an opening of the bushing. A piston 80 is reciprocably operable in the cylinder and is connected with the piston rod 18. Compressed air or other suitable motive fluid is supplied to or exhausted from the cylinder through the conduit connections 81 and 82 to cause lifting or lowering of the annular ejector 49. The operation of the cylinder 24 is controlled by the valve 26 which is of a conventional construction and operates such that movement of its lever 83 in one direction will cause lifting of the ejector 49 and movement of the lever in the opposite direction will cause the ejector to be lowered or retracted.

The amount of bending to which the legs of the coils 10 are subjected depends upon the amount of relative angular movement produced between the sleeves 31 and 32 and the die rings 28 and 29 carried thereby. This angular movement is limited in extent by suitable stop means such as the stop screw 84 which is mounted on the base plate 22 and is adapted to be engaged by the outer end of the rack 61. Adjusting nuts 85 provided on the screw 84 permit the same to be adjusted for varying the amount of relative angular movement permitted between the die rings 28 and 29.

From the foregoing description and the accompanying drawings it will now be readily understood that this invention provides an improved coil shaping machine which is relatively simple in construction and which operates in an efficient manner to form or bend electrical coils to a desired shape.

Although the coil shaping machine of the present invention has been illustrated and described herein in considerable detail, it will be understood of course that the invention is not to be regarded as being limited correspondingly but includes all changes and modifications coming within the scope of the claims hereof.

Having thus described my invention, I claim:

1. In a machine for shaping electrical coils of the hairpin type having substantially parallel conductor bar portions prior to assembly of the coils in a magnet member, a pair of substantially coaxially disposed die members having opposed annular portions containing rows of slots adapted to receive therein the parallel bar portions of an annular series of said coils, the slots of said opposed annular portions being of an axial length

such that the ends of said bar portions project therefrom, means mounting said die members for arcuate relative movement so as to cause bending of said bar portions to a desired shape, means for causing such arcuate relative movement between the die members, and ejecting means movable axially of said pair of die members and having an annular portion engageable with the projecting ends of the bar portions of said coils.

2. In a machine for shaping electrical coils of the type having substantially parallel conductor bar portions connected at one end by a substantially U-shaped bend prior to assembly of the coils in a magnet member, a pair of die members provided with slots adapted to receive therein the parallel bar portions of a series of said coils, a third die member having slots adapted to receive therein the U-shaped bends of said coils, means mounting said pair of die members so as to permit relative movement therebetween of a predetermined extent for causing the die members to bend said bar portions to a desired shape, means for positioning said third die member relative to said pair of die members so as to enable said third die member to engage said U-shaped bends for holding said series of coils during the bending of said bar portions, and actuating means for causing such relative movement between the die members of said pair.

3. In a machine for shaping electrical coils of the type having substantially parallel conductor bar portions connected at one end by a substantially U-shaped bend prior to assembly of the coils in a magnet member, a pair of substantially coaxially disposed die members having annular rows of slots adapted to receive therein the parallel bar portions of an annular series of said coils, a third die member having an annular row of slots adapted to receive therein the U-shaped bends of said coils, means mounting said pair of die members for arcuate relative movement for causing the die members to bend said bar portions to a desired shape, means for positioning said third die member relative to said pair of die members so as to enable said third die member to engage said U-shaped bends for holding said series of coils during the bending of said bar portions, and actuating means for causing such arcuate relative movement between the die members of said pair.

4. In a machine for shaping electrical coils of the type having substantially parallel conductor bar portions connected at one end by a substantially U-shaped bend prior to assembly of the coils in a magnet member, a pair of substantially coaxially disposed die members having opposed annular portions containing rows of slots adapted to receive therein the parallel bar portions of an annular series of said coils, the slots of said opposed annular portions being of a length such that the free ends of said bar portions project therefrom, a third die member having an annular row of slots adapted to receive therein the U-shaped bends of said coils, means mounting said pair of die members for arcuate relative movement for causing the die members to bend said bar portions to a desired shape, means for positioning said third die member relative to said pair of die members so as to enable said third die member to engage said U-shaped bends for holding said series of coils during the bending of said bar portions, actuating means for causing such arcuate relative movement between the die members of said pair, and ejecting means movable axially of said pair of die members and hav-

ing an annular portion engageable with the projecting ends of said bar portions of said coils.

5. In coil shaping apparatus, a pair of relatively rotatable sleeves disposed in substantially coaxial relation with an annular space therebetween, said sleeves having annular die means at their outer ends which overhang said space and are provided with axial slots adapted to receive portions of the coils to be shaped, an annular ejector member in said space and forming a support adapted to be engaged by the inner ends of the coils, means for producing relative arcuate movement between said sleeves for causing bending of the coils to a desired shape by said die means, and means for moving said ejector member axially in said space.

10 6. In apparatus for shaping electrical coils of the hairpin type having bar and loop end portion, a pair of substantially coaxially disposed annular die members having opposed peripheral portions provided with complementary slots adapted to receive said bar portions of the coils to be shaped while said end loop portions of the coils project from said die members, a third die member having an annular portion provided with slots in which the end loop portions of said coils engage, means mounting the die members of said pair for relative arcuate movement for causing bending of said bar portions, means for positioning said third die member relative to said pair of die members so as to enable said third die member to engage said end loop portions for holding said coils during the bending of said bar portions and also permitting said third die member to have both arcuate and axial movement, and means for producing relative arcuate movement between the die members of said pair.

20 7. In coil shaping apparatus, a pair of substantially coaxially disposed annular die members having opposed peripheral portions provided with complementary slots adapted to receive lower portions of the coils to be shaped, a floating die member capable of axial and arcuate movement 25 and having an annular portion provided with vertically disposed spaced slots in which upper portions of said coils are adapted to engage, said floating die being adapted to be supported on the coils and being weighted for retaining the 30 slots thereof in engagement with said upper portions of the coils, and means for producing relative arcuate movement between the die members of said pair.

35 8. In coil shaping apparatus, a pair of relatively rotatable inner and outer sleeves disposed in substantially coaxial relation with an annular space therebetween, said sleeves having annular die portions at their outer ends which overhang said space and are provided with axial slots 40 adapted to receive portions of the coils to be shaped, an annular ejector member in said space and forming a support adapted to be engaged by one end of the coils, said ejector member having a retracted position relative to the slotted die 45 portions such that the other ends of the coils project from said slotted die portions, a third die member having a stem portion extending into the inner sleeve and an annular shoulder provided with radial slots in which said other ends 50 of the coils are engageable, said third die member being weighted for holding the same in engagement with the coils and being axially and 55 arcuately movable relative to said sleeves, means for producing relative arcuate movement between 60 said sleeves for causing bending of the 65 coils.

coils to a desired shape, and means for moving said ejector member axially in said space.

9. A coil shaping machine of the character described comprising, a support, a gear member pivotally mounted on said support, an upright sleeve carried by said gear member and arcuately movable therewith, a second upright sleeve fixed on said support and extending coaxially with the first sleeve, said sleeves having complementary die rings thereon provided with annular rows of axial slots in their adjacent peripheries and which slots are adapted to receive portions of the coils to be shaped, a power device on said support and having operative connection with said gear member for imparting arcuate movement to said first sleeve, a member axially and arcuately movable in the inner one of the coaxial upright sleeves, and a third die ring carried by the last mentioned member and having an annular row of slots in which the tops of said coils are adapted to engage.

10. A coil shaping machine of the character described comprising, a support, a gear member pivotally mounted on said support, an upright sleeve carried by said gear member and arcuately movable therewith, a second upright sleeve fixed on said support and extending coaxially with the first sleeve with an annular space therebetween, said second sleeve having axial openings in the wall thereof, complementary die rings on said sleeves and provided with annular rows of slots in their adjacent peripheries and which slots are adapted to receive portions of the coils

to be shaped, an annular ejector member in said space and forming a support adapted to be engaged by the lower ends of said coils, actuating means for said ejector including arms movable in said axial openings, a weighted member axially and arcuately movable in the inner one of the coaxial upright sleeves, a third die ring carried by said weighted member and having an annular row of slots in which the tops of said coils are adapted to engage, and power means adapted to act on said gear member for actuating the movable sleeve.
